UNITED STATES PATENT OFFICE

ROBERT P. MUNGER, OF SIOUX CITY, IOWA

BARBER POLE

Application filed August 5, 1929. Serial No. 383,689.

This invention relates to advertising devices and more particularly to the illuminated types of barber poles.

An object of the invention contemplates the provision and arrangement of a sign board for tonsorial parlors having a plurality of paneled compartments.

Another object of the invention embodies the provision of illuminating means for each 10 of the compartments selectively operable to give the effect of a jumping barber pole.

More specifically stated the panels of the compartments may be provided with stencils to advertise certain matter descriptive of the 15 trade.

With the above and other objects in view, the invention further consists of the following novel features and details of construction, to be hereinafter more fully described, 20 illustrated in the accompanying drawings and pointed out in the appended claim.

In the drawings:—

Figure 1 is a front elevation of the invention.

25 Figure 2 is a rear elevation thereof with the back removed.

Figure 3 is a front elevation of the back and partition carried thereby.

Figure 4 is a horizontal sectional view 30 taken on line 4—4 of Figure 1.

Figure 5 is a detail sectional view taken through an end of the device and illustrative of the connection of the panels upon the bottom and the arrangement of the stencils.

35 Figure 6 is a horizontal sectional view taken on line 6—6 of Figure 3.

Referring to the drawings in detail wherein like characters of reference denote corresponding parts, the reference characters 10 and 11 indicate the top and bottom pieces of the improved form of pole, each of which having grooves or recesses 12 adjacent the marginal edges thereof of meeting side portions. Panels, such as indicated at 13, preferably formed of glass, have the ends thereof fitted within the recesses 12 in the manner shown in Figures 4 and 5 of the drawings.

A parting strip 14, having connection at its ends with the top and bottom pieces, is disposed for contacting engagement with the ad-

jacent side edges of the obliquely disposed panels. A back or cover 15, secured to the top and bottom pieces after the manner of the parting strip 14 and engageable with the side edges of the panels 13 to force same against the parting strip 14, also carries a partition 16 to facilitate subdividing of the pole into separate compartments. If desired, a form of stencil 17 may be employed of strip-like formation lying flush with the inner sides of the panels and fitted within the grooves or recesses 12. The remaining portions of the panels, uncovered by the stencils, are designed to exhibit stripes of even width in red, white and blue colors, after the manner of the conventional barber pole, but in this instance like colored stripes upon each of the panels are upwardly and obliquely inclined toward common apices located behind the parting strip 14. Lamp sockets, indicated as at 18, carried upon the back 15 and projecting within each of the compartments, are to be furnished with flasher buttons or like intermittent automatic switches in order that the different compartments will be selectively and alternately illuminated to give the effect of a jumping barber pole.

It is thought that the present invention will prove more attractive than the customary stationary or revolving types of barber advertisements in view of the novel effect of a jumping rather than a spiraled pole.

The invention is susceptible of various changes in its form, proportions and minor details of construction, and the right is herein reserved to make such changes as properly fall within the scope of the appended claim.

Having thus described the invention, what is claimed is:—

A barber pole display device comprising top and bottom pieces of triangular formation having grooves upon the inner faces thereof adjacent their meeting sides, a partition of triangular formation disposed intermediate the distance between the top and bottom pieces, a parting strip having connection with the pieces and partition, panels of translucent formation positioned terminally within said grooves and faced with different colored equidistantly spaced upwardly 90 95 100

and obliquely inclined stripes to define common apices behind the parting strip, and a back for the device including electrically operated means to selectively intermittently and alternately illuminate said compartments whereby the peculiar effect of a jumping barber pole will be exhibited.

In testimony whereof I affix my signature.

ROBERT P. MUNGER.
